UNITED STATES PATENT OFFICE.

JOSEPH H. LEIDEL, OF DRESBACH, MINNESOTA.

CORN-HUSKING MACHINE.

No. 845,957.

Specification of Letters Patent.

Patented March 5, 1907.

Application filed December 29, 1905. Serial No. 293,812.

To all whom it may concern:

Be it known that I, JOSEPH H. LEIDEL, a citizen of the United States, residing at Dresbach, in the county of Winona and State of Minnesota, have invented certain new and useful Improvements in Corn-Husking Machines, of which the following is a specification.

This invention aims to devise a novel mechanism for husking corn after the same has been harvested and cured and the ears snapped from the stalks.

The invention contemplates in combination with a pair of husking-rolls a lifter for detaching the ears from one of the husking-rolls at a point in its travel to admit of the other husking-roll turning the ears to bring the part previously uppermost in a lower position or in such relation as to insure 20 thorough removal of the husks and corn-silk from the ears.

The invention further contemplates peculiar means for directing the ears to the husking-rolls, whereby the latter promptly 25 and effectively take hold of the husks and strip them from the ears, said means serving to properly position the ears in their delivery to the husking mechanism.

For a full description of the invention and 30 the merits thereof and also to acquire a knowledge of the details of construction of the means for effecting the result reference is to be had to the following description and accompanying drawings.

While the invention may be adapted to 35 different forms and conditions by changes in the structure and minor details without departing from the spirit or essential features thereof, still the preferred embodiment is 40 shown in the accompanying drawings, in which—

Figure 1 is a front view of a corn-husking machine embodying the invention, the housings of the several pairs of rollers being 45 omitted and one pair of rollers, its gearing, and mountings being in section. Fig. 2 is a front view of the machine, a portion of one of the housings being broken away. Fig. 3 is a vertical longitudinal section of the machine 50 on the line 3 3 of Fig. 2. Fig. 4 is a transverse section of the husking mechanisms, their housings, and the supporting framework. Fig. 5 is a fragmentary perspective view showing the feed-board and guiding 55 means.

Corresponding and like parts are referred

to in the following description and indicated in all the views of the drawings by the same reference characters.

The husking mechanism is preferably inclined to cause the ears to feed by gravitational force, thereby obviating the necessity for providing feeding mechanism of any kind for advancing the ears during the process of stripping the husks therefrom. In the present instance the husking mechanism comprises a pair of husking-rolls, which are arranged with longitudinal edge portions practically in contact, said rolls being geared for simultaneous rotation in opposite directions, whereby their opposing sides move in unison so as to draw the husks from the ears and cause said husks to pass between them. The husking-rolls are disposed in parallel relation and are positively geared by means of cog-wheels, which are fast to extensions of their journals or shafts. There may be as many pairs of husking-rolls as desired, each with its adjunctive devices being a duplicate of the other.

The husking-rolls comprising a pair are represented by the numerals 1 and 2, the same being journaled in bearings applied to cross-timbers 3 and 4, which form elements of a framework. A cog 5 is fast to an extension of the journal or shaft of each husking-roll, the cog-wheels 5 being of like diameter and having an equal number of teeth to compel the husking-rolls to rotate at a like speed and in opposite directions, whereby the upper portion of each bordering upon the trough or space formed between them travels inward and downward, with the result that the husking-rolls mutually coöperate to strip the husks from the ears and deliver the said 95 husks between them. Each husking-roll is provided with two rows of teeth 6 and annular grooves 7, the latter alternating with the teeth. The teeth upon one husking-roll are arranged opposite to the annular grooves of the companion husking-roll, so as to enter the same in the rotation of the rolls. The teeth 6 are provided in two straight lines, which are located upon diametrically opposite sides of a husking-roll, the teeth being of chisel form and projecting from the rolls a comparatively short distance, so as not to injure the grain or kernels. A housing 8 is arranged over the upper portion of the husking-rolls and prevents the ears flying from or leaving the husking-rolls during the operation of stripping the husks from the ears.

The housing 8 is preferably of semicircular form in cross-section and consists of a metal covering, the side portions of which fit close to the outer sides of the husking-rolls, so as to not interfere with the free operation thereof or come in contact with the teeth thereof.

To effect a thorough removal of the husks and corn-silk, it has been found desirable to employ one or more lifters 9, which are arranged with reference to a husking-roll to carry the ears free thereof, while the other or companion husking-roll effects a turning of the ears to bring the part remote from the husking-rolls in position to be acted upon, so that any portion of the husk or corn-silk clinging thereto may be removed. The lifter 9 consists of a plate in the preferable construction and is arranged in the length of the husking-rolls and path of travel of the ears, so as to support the latter during a part of their travel over one of the husking-rolls and while the other husking-roll is serving to turn the same. The plate 9 is preferably of sheet material, such as metal, and is transversely corrugated, fluted, or ribbed with reference to the path of travel of the ears or the length of the husking-rolls, with the result that the ears are prevented from passing too rapidly over the lifter and are sufficiently retarded to insure their turning by the other or active husking-roll. The lifter is arranged over the upper inner portion of a husking-roll and wholly to one side of the space formed between the upper proximal portions of the husking-rolls. By employing more than one lifter and spacing the same apart the ears are turned a number of times, thereby insuring a thorough removal of the husks and corn-silk therefrom, which is desirable in order not to detract from the commercial value of the product.

Any suitable framework may be devised for supporting the husking mechanism and adjunctive parts. As shown, the framework comprises longitudinal base timbers 10, uprights 11, longitudinal timbers 12, and the cross-timbers 3 and 4. The longitudinal timbers 12 are inclined corresponding to the inclination of the husking-rolls. The upper portion of the framework receives the hopper and directing means for guiding the ears to the husking mechanism. The directing means comprises a feed-board 13 and upwardly-diverged guides 14, the latter being spaced from the feed-board a distance to admit of the ears passing freely into the hopper and from thence to the husking-rolls. Side pieces 15 prevent the ears from passing over the ends of the feed-board and compel said ears to occupy a position so as to ultimately enter the hopper or hoppers preliminary to passing upon the husking-rolls. Each pair of husking-rolls is provided with a hopper 16, the ends and sides of which slope or incline inwardly and downwardly to cause the ears

to be received in the space formed between the inner and upper portions of a pair of husking-rolls. A spur 17 is located at the lower end of the feed-board in line with the space formed between a pair of husking-rolls and in line with the center or angle formed between the side portions comprising the cooperating diverged guide 14. The purpose of the spur 17 is to prevent an ear entering the hopper crosswise and to effect a turning of the ears, so that they will enter the hopper endwise or approximately parallel with the length of the husking-rolls, so as to promptly be taken up by the husking mechanism, and thereby avoid any possible loss of time and prevent choking or obstructing of the machine. The ears are also positioned by the guide 14, the diverged members of which centralize the ears and cause the same to pass quickly to the center of the space formed between the companion husking-rolls.

A counter-shaft 18 is arranged crosswise of the framework and is journaled at or near its ends in bearings secured to the side timbers 12, and said shaft is driven from a suitable source of power in any convenient way and, as shown, is provided with a sprocket-wheel 19, around which is adapted to be passed a sprocket drive-chain (not shown) in the usual way. A bevel spur-gear 20, fast upon the counter-shaft 18, is in mesh with a companion spur-gear 21, fast upon the extended journal or shaft of a husking-roll. In the event of a series of husking mechanisms being embodied in one machine each pair of husking-rolls is operated in the manner specified.

In the operation of the machine the ears of corn to be husked are fed to the board 13 by hand or in any manner found most advantageous, and said ears pass from the board into the hopper, being properly positioned by the spur 17 and the guide 14 in the manner stated. As the ears are received upon the husking-rolls the teeth 6 penetrate the husks and tear or strip the latter therefrom, said husks being drawn between the rolls and dropped therefrom after being drawn between the rolls. As the ears in their travel come in contact with the lifter or lifters they are temporarily disengaged from one husking-roll and at this time are turned by the other husking-roll so as to bring a new portion in position to be acted upon by the husking mechanism, with the result that any portion of the husk or corn-silk adhering thereto is removed. The housing or covering 8 holds the ears in position and prevents any turning thereof during their travel over the husking-rolls.

Having thus described the invention, what is claimed as new is—

1. In corn-husking mechanism, the combination of complementary husking elements, and means arranged in the path of the ears

and adapted to temporarily remove the ears during their travel from the action of one of the husking elements to admit of the other husking element turning the ears to bring a 5 new portion thereof in position for the action of the husking elements during the remainder of the travel of said ears thereover.

2. In husking mechanism, the combination of complemental husking elements, and 10 a litter arranged in the path of the ears to effect temporary disengagement thereof from one of the husking elements, said litter being corrugated or roughened to prevent a too rapid movement of the ears thereover.

15 3. The combination of a pair of husking-rolls, and a litter arranged to extend over the inner upper portion of one of said husking-rolls and in close proximity thereto to effect temporary disengagement of the ears therefrom and to permit turning of said ears by 20 the companion husking-roll, substantially as and for the purpose specified.

4. In combination, husking mechanism, 25 guide means for directing the ears to the husking mechanism, and a spur located in advance of the receiving end of the guide means to prevent the ears entering the husking mechanism crosswise.

5. In combination, corn-husking mechan-

ism, and a guide comprising upwardly and 30 forwardly diverged members to insure endwise entrance of the ears to said husking mechanism.

6. In combination, a husking mechanism, a hopper comprising inwardly or downwardly 35 sloped or inclined walls, an inclined feed-board, a spur at the lower edge of said feed-board and in line with the space formed between the husking elements, and a guide between the hopper and husking mechanism 40 comprising upwardly and forwardly diverged members.

7. In combination, husking mechanism embodying coöperating husking-rollers, and 45 a litter arranged in the path of movement of the ears to effect temporary disengagement therefrom from one of the husking-rollers to permit the other roller to effect turning of said ears, said litter comprising a curved plate arranged over and concentric with one of the 50 rollers, as specified.

In testimony whereof I affix my signature in presence of two witnesses.

JOSEPH H. LEIDEL. [L. S.]
